UNITED STATES PATENT OFFICE

107,668

DESIGN FOR A MINIATURE CHRISTMAS TREE

Sidney C. Wadsworth and Fred Bell, Lake Forest,
III.

Application September 8, 1937, Serial No. 71,504

Term of patent 7 years

To all whom it may concern:

Be it known that we, Sidney C. Wadsworth and Fred Bell, citizens of the United States, residing at Lake Forest, in the county of Lake and State of Illinois, have invented a new, original, and ornamental Design for a Miniature Christmas Tree, of which the following is a specification, reference being had to the accompanying drawing, forming part thereof.

The figure is a perspective view of the tree showing our new design.

We claim:

The ornamental design for a miniature Christmas tree, as shown.

SIDNEY C. WADSWORTH.
FRED BELL.
